(57) **CLAIM**

The ornamental design for a dispensing bottle, as shown and described.

DESCRIPTION

FIG. 1 is a front elevational view of a dispensing bottle showing my new design, the rear view being identical;

FIG. 2 is a side elevational view thereof, the opposite side being identical;

FIG. 3 is a top plan view thereof; and,

FIG. 4 is a bottom plan view thereof.

The broken line showing of a lid is included for the purpose of illustration and forms no part of the claimed design.
